HOSE NOZZLE

William L. Lockett, Downers Grove, Ill., assignor to
W. D. Allen Manufacturing Co., Chicago, Ill., a cor-
poration of Illinois

Application November 10, 1958, Serial No. 53,314
Term of patent 14 years

(Cl. D91—1)

FIG. 1

FIG. 2 + 4

FIG. 3

FIG. 4

Fig. 1 is a perspective view of the hose nozzle embodying the new design;

Fig. 2 is a side elevational view of the hose nozzle shown in Fig. 1;

Fig. 3 is an end elevational view of the hose nozzle shown in Fig. 1 and looking at the water discharge end thereof; and

Fig. 4 is a transverse sectional view of the hose nozzle of Fig. 1, taken substantially along line 4—4 of Fig. 2.

The dominant features of the hose nozzle reside in the portions shown in solid lines.

I claim:

The ornamental design for a hose nozzle, as shown and described.
